UNITED STATES PATENT OFFICE.

WILLIAM C. STEWART, OF SWAMPSMOTT, MASSACHUSETTS, ASSIGNOR TO UNITED SHOE MACHINERY COMPANY, OF PATERSON, NEW JERSEY, A CORPORATION OF NEW JERSEY.

DISPENSING DEVICE.

1,248,746.

Specification of Letters Patent.

Patented Dec. 4, 1917.

Application filed December 5, 1916. Serial No. 135,130.

To all whom it may concern:

Be it known that I, WILLIAM C. STEWART, a subject of the King of England, residing at Swampscott, in the county of Essex and 5 State of Massachusetts, have invented certain Improvements in Dispensing Devices, of which the following description, in connection with the accompanying drawings, is a specification, like reference characters 10 on the drawings indicating like parts in the several figures.

This invention relates to a dispensing device and especially to such a device adapted for use with inflammable fluids so as to prevent 15 danger from fire.

Most sorts of liquid cement for use in cementing leather, rubber and the like, are highly inflammable and if exposed in an ordinary receptacle they deteriorate and are 20 liable to catch fire.

The general object of this invention is to provide a receptacle for use with such fluids which shall protect the user and surrounding material from the danger of fire. A 25 further object is to devise a barometric dispensing device which is provided with an improved brush cup.

The invention will be more readily understood from the following specification taken 30 in connection with the accompanying drawings, in which—

Figure 1 is a side elevation of the improved dispensing device;

Fig. 2 is a detail of the retaining latch 35 for the spring-pressed cover; and

Fig. 3 shows a modified form of the receptacle and the latch.

The barometric dispensing receptacle illustrated in Fig. 1 will be seen to comprise an 40 air-tight main receptacle 10 normally supported upon feet 12 and 14 and provided with an auxiliary receptacle 16 which communicates with said main receptacle at a point 18 below the normal level of the fluid 45 in the auxiliary receptacle. Similar constructions are well known in the art and their operation need not be further explained. In order that the user and adjacent inflammable material may be protected 50 in case the fluid in the auxiliary receptacle ignites, a cover 20 is pivoted on the main receptacle and is pressed downwardly to close the auxiliary receptacle by means of a spring 22. This cover may be retained in 55 open position by means of a latch arm piv-

oted to a lug 24 and made up of two members 26 and 28 between whose outer ends is mounted a retaining finger 30. This finger is pivoted within said arms upon a pivot 32 but is normally held in the position, shown in 60 full lines in the drawing, by means of soft solder having a low melting point between the member 30 and said arms. The arm 26 is preferably provided with extensions, as shown in Fig. 1, to limit its movement 65 upon the lug 24. When the cement or other fluid in the receptacle ignites, the heat caused thereby will melt the solder and allow the member 30 to rotate to the position shown in dotted lines in Figs. 1 and 2, thereby 70 releasing the cover 20 which will be closed by the action of the spring 22. Obviously, this spring may be omitted and the action of gravity relied on if desired. When it is desired to fill the receptacle, it will be rotated clockwise and supported upon the leg 12 and the lug 34. Cement or other fluid may then be introduced through the auxiliary receptacle 16 to fill the main receptacle. The opening of the auxiliary receptacle 16 80 is preferably divided by a partition whose lower edge is shown in dotted lines at 36 so that during the filling of the receptacle with a viscous fluid the throat 18 will not be choked and a free escape of air from the 85 main receptacle allowed.

It is common in such devices to provide a cup which may be filled with water for the reception of the brush used with the fluid dispensed by the receptacle in order 90 to keep the brush in good condition. If such a cup is provided upon a barometric dispensing device, it will obviously be open to the objection that its contents will be spilled when the receptacle is partially inverted for filling. Accordingly, there has been provided in connection with this improved dispensing device not only the normal brush cup 38 but also an auxiliary cup 40 which may conveniently be formed integrally with the cup 38 and the main receptacle. This cup is so related to the cup 38 that when the device is partially inverted for filling, the contents of the cup 38 will drain into the cup 40 and will not be spilled. 95 100

With certain kinds of adhesives, one of which is known to the trade as "hazenite", an air-tight receptacle such as is found in a barometric dispensing device is undesirable because a gas is developed in the hazen- 105 110

ite which tends to force the fluid out irregularly into the auxiliary receptacle. This adhesive is viscous and a modified receptacle 42, shown in Fig. 3, is especially adapted for its use. This modified form 42 will be seen to comprise a main receptacle, having a sloping bottom 43, mounted upon the base 44. A cover 46 is provided which is not air-tight but will serve to prevent the exposure of the main body of the fluid to sparks or flame. Because of the loose fit of this cover, it will act as a safety valve to permit the escape of gas liberated by the fluid, thereby preventing the scattering of the contents by an explosion. The auxiliary receptacle 48 connects with the main receptacle through a passage 50 and the flow into said auxiliary receptacle is controlled by means of a gate 52 sliding vertically in guides 54 and controlled by a handle 56. A groove 57 is provided between the sloping bottom 43 and the wall of the receptacle 42 for the reception of the lower edge of this gate. The fluid in the auxiliary receptacle is similarly protected, as in the form shown in Fig. 1, by means of a cover 58 pivoted to the receptacle and urged to closed position by a spring 60. This cover is retained in open position by means of a latch arm 62 which is provided at its outer end with a retaining member 64 attached to the arm 62 by solder having a low melting point. This operation is similar to that described in connection with Fig. 1.

Having thus described my invention, what I claim as new and desire to secure by Letters Patent of the United States is:

1. In a receptacle for inflammable fluids, a main receptacle substantially closed to protect the contents against sparks and fire, an auxiliary receptacle connected to the

main receptacle and communicating with the interior thereof, said auxiliary receptacle being adapted to receive a small quantity of the inflammable fluid for removal by the user, a cover for said auxiliary receptacle arranged to close automatically when released, a latch for holding said cover in open position, said latch being constructed and arranged so that it is rendered inoperative by the presence of heat such as might be caused by the ignition of fluid in the auxiliary receptacle.

2. A barometric dispensing receptacle for inflammable fluids comprising an air-tight main receptacle, an auxiliary receptacle communicating therewith below the normal level of the fluid in the main receptacle, a spring-pressed cover for said receptacle, a latch arm attached to said main receptacle and provided near its outer end with a retaining finger held in place by solder having a low melting point.

3. A barometric dispensing device comprising a main receptacle, an auxiliary receptacle communicating therewith below the normal level of the fluid in the auxiliary receptacle, said main receptacle adapted to be partially inverted for filling, a water cup open at the top and mounted on the exterior of said main receptacle for the reception of a brush when the dispensing device is in normal position and an auxiliary cup connected with the first cup and arranged to receive the contents of the same when the dispensing device is partially inverted for filling.

In testimony whereof I have signed my name to this specification.

WILLIAM C. STEWART.
